UNITED STATES PATENT OFFICE.

EDWIN WALKER, OF ERIE, PENNSYLVANIA.

DESIGN FOR A LIME-SQUEEZER.

48,269.

Specification for Design.

Patented Dec. 7, 1915.

Application filed April 4, 1913. Serial No. 758,954. Term of patent 14 years.

To all whom it may concern:

Be it known that I, EDWIN WALKER, a citizen of the United States, residing at Erie, in the county of Erie and State of Pennsylvania, have invented a new, original, and ornamental Design for a Lime-Squeezer, of which the following is a specification, reference being had to the accompanying drawing, forming a part thereof.

Figure 1 is a top plan view. Fig. 2 is a bottom plan view. Fig. 3 is an elevation

looking toward the left in Fig. 1. Fig. 4 is a cross-section taken on line 4-4 of Fig. 2, showing the contour of the handles at this point.

I claim—

The ornamental design for a lime squeezer, as shown.

EDWIN WALKER.
